UNITED STATES PATENT OFFICE.

WILLIAM A. LIGHTHALL, OF NEW YORK, N. Y.

IMPROVEMENT IN POTABLE-WATER CONDENSERS.

Specification forming part of Letters Patent No. 35,029, dated April 22, 1862.

To all whom it may concern:

Be it known that I, WILLIAM A. LIGHTHALL, of the city, county, and State of New York, have invented a certain new and useful Improvement in Condensers for Making Potable Water from Salt or other Water Unfit for Potable Purposes; and I do hereby declare that the following is a full and exact description of the same, reference being had to the accompanying drawings, and to the letters of reference marked thereon, in which—

Figure 1 is a central longitudinal vertical section; and Fig. 2, a transverse section taken through the line $x x$, Fig. 1.

My invention is an improvement upon the one secured to me by Letters Patent of the United States bearing date of December 17, 1861; and it consists in combining with the condenser shown and described in said Letters Patent (to which reference is hereby made) a series of tubes placed beneath the drip-plate for the purpose of cooling the condensed water after passing through the drip-plate into the drip-reservoir prior to its being taken off or away from the condenser to the tanks or other receptacles placed to receive it.

The case of the condenser, its division-plates and tubes, and its drip-plate and drip-reservoir being constructed and arranged the same as those shown and described in the Letters Patent above named, the only alteration (constituting in its combination with the above my improvement) is that the drip-reservoir A is fitted with a series of tubes, B, through which a portion of the supply of cooling water that is supplied to the condenser in its upper section of tubes to condense the steam is passed to cool the condensed water as it passes into the drip-reservoir A, and before it is carried off from the condenser to the tanks or other receptacles fitted to receive it.

What I claim as my invention, and desire to secure by Letters Patent, is—

The combination, with the drip-reservoir A and drip-plate E, of the series of cooling-tubes B, arranged and operated as and for the purpose herein set forth.

WM. A. LIGHTHALL.
